UNITED STATES PATENT OFFICE

108,843

DESIGN FOR A HEAD BAND OR SIMILAR ARTICLE

Harry Charney, Brooklyn, N. Y.

Application January 14, 1938, Serial No. 74,308

Term of patent 3½ years

To all whom it may concern:

Be it known that I, Harry Charney, a citizen of the United States of America, residing at Brooklyn, in the county of Kings and State of New York, have invented a new, original, and ornamental Design for a Head Band or Similar Article, of which the following is a specification, reference being had to the accompanying drawing, forming a part thereof.

In the drawing:

Fig. 1 is a front perspective view of the head band showing my design.

Fig. 2 is a rear perspective view of the head band shown in Fig. 1.

Fig. 3 is a front view of the head band shown in Fig. 1 in open position.

The characteristic feature of my design resides in the longitudinally pleated band, knotted at the center, in combination with the buckle, as shown.

I claim:

The ornamental design for a head band or similar article, as shown and described.

HARRY CHARNEY.
